United States Patent Office.

MRS. ELIZA J. HARDING, OF ST. LOUIS, MISSOURI.

Letters Patent No. 75,902, dated March 24, 1868.

IMPROVEMENT IN ABDOMINAL AND UTERINE SUPPORTERS.

The Schedule referred to in these Letters Patent and making part of the same.

TO ALL WHOM IT MAY CONCERN:

Be it known that I, Mrs. ELIZA J. HARDING, of St. Louis, in the county of St. Louis, and State of Missouri, have made certain new and useful Improvements in Abdominal and Uterine Supporter; and I do hereby declare that the following is a full and clear description thereof, reference being had to the accompanying drawings, and to the letters of reference marked thereon.

The object of this invention is to produce a supporter which may easily be worn by ladies at seasons of maternity without trouble, pain, or inconvenience, and which will allay or prevent puerperal disorders of the *prolapsus* variety, and at the same time will be equally well adapted to severe or chronic cases of *prolapsus uteri*. The apparatus consists of two pads, coupled together by means of elastic bands, which hold them in their proper positions on the person of the wearer.

To enable those skilled in the art to make and use my improved abdominal and uterine supporter, I will proceed to describe its construction and operation.

Figure 1 of the drawings is a perspective view of one of the improved apparatus in its distended position as applied to the person of a wearer.

Figure 2 is a perspective view of the apparatus in another position.

The apparatus consists of an anterior pad, A, and a posterior pad, A'. The two upper corners of the pad A are to be connected with the opposite and corresponding corners of the pad A' by means of the superior bands *a*, which pass around the exterior sides of the hips, while the lower ends of the pads A A' are connected together by the inferior bands *a'*, which pass around the interior sides of the hips. The pads A A' are to be of leather or vulcanized rubber, and covered with some pliable textile fabric. The pad A is to be somewhat V-shaped in form, so as to fit the exterior surface of the *pelvis viscera*, and thereby be capable of exerting a gentle pressure upon the *os pubis*. The upper or wider end of this pad will extend across the abdomen in a line parallel with the lower rib. The pad A' will be nearly oval in form, and of such a size as will be readily adaptable to the form at the base of the spinal column. The bands *a a'* are to be of some elastic material, and are to be secured to the pads by means of the buttons *a²*, suitable holes being worked in the said bands for the reception of the said buttons. Additional holes, *a³*, may be made in the bands *a a'*, so as to fit the apparatus to a form more or less rotund. Attachments, *a⁴*, are to be provided at the base of the pads A A', for securing a pessary or other similar device thereto, in case such should have to be worn. A diagonal bracing-band, B, should be taken around the exterior part of the hip, so as to brace the apparatus, and hold it firmly in place. This bracing-strap is to be secured by buttons, as is clearly shown.

One great improvement in this device over all others now in use consists in the arrangement of the pad A', which in this case not only serves as a point of attachment and support for the pad A, but also serves as a valuable support and counterbrace to the spinal column in the vicinity of the kidneys, and thus aids nature to recuperate its energies in one very vital point of weakness.

Having described my invention, what I claim, is—

The pads A A' and the bands *a a'*, when constructed and employed as herein shown, and for the purpose set forth.

MRS. E. J. HARDING.
